United States Patent Office

Des. 185,618
Patented June 30, 1959

185,618

WATER CLOSET

Walter D. Teague, Annandale, N.J., and Robert H. Ensign, Bronxville, N.Y., assignors to American Radiator & Standard Sanitary Corporation, New York, N.Y., a corporation of Delaware

Application December 9, 1955, Serial No. 39,260

Term of patent 14 years

(Cl. D4—5)

Fig. 1 is a perspective view of a water closet shown in reduced scale embodying our new design,

Fig. 2 is a top plan view thereof;

Fig. 3 is a view in side elevation of the water closet;

Fig. 4 is a view in front elevation of the water closet; and

Fig. 5 is a view in rear elevation thereof.

We claim:

The ornamental design for a water closet, substantially as shown.
